[57] CLAIM

The ornamental design for a holder for toilet articles, as shown and described.

DESCRIPTION

FIGS. 1, 2 and 3 are front and right side perspective views, respectively, of a holder for toilet articles, showing my new design, with the outer rotatable cover thereof in alternative positions;

FIG. 4 and 5 respectively are enlarged fragmentary perspective view thereof;

FIG. 6 is a rear and right side perspective view thereof. The top and bottom ends, the wall brackets, and shelves are of a contrasting color as compared with that of the walls and cover.
